UNITED STATES PATENT OFFICE.

BENJAMIN KOTKOVSKY, OF BROOKLYN, GEORGE LUTER, OF NEW YORK, AND BORIS DUBI, OF BROOKLYN, NEW YORK, ASSIGNEES TO CHAINLESS KNITTING MACHINE CORP., OF NEW YORK, N. Y., A CORPORATION OF NEW YORK.

ADJUSTABLE AUTOMATIC KNITTING MACHINE.

Application filed August 3, 1922. Serial No. 579,459.

To all whom it may concern:

Be it known that we, BENJAMIN KOTKOVSKY, GEORGE LUTER, and BORIS DUBI, respectively a citizen of Russia and citizens 5 of the United States, and residents, respectively, of the borough of Brooklyn, county of Kings, State of New York, borough of Manhattan, county of New York, State of New York, and borough of Brooklyn, county of 10 Kings, and State of New York, have jointly invented certain new and useful Improvements in Adjustable Automatic Knitting Machines, of which the following is a specification.

15 This invention relates to improvements in adjustable automatic knitting machines.

The object of the invention is the production of means to produce knitted material 20 of predetermined lengths. Its second object is the production of a knitted material with stitches of various designs and combinations and colors. The third object of 25 the invention is the production of means whereby the various adjustments thereof can be easily controlled by the operator. The fourth object of the invention is the production of a knitting machine whereby the speed of operation is greatly increased. A fifth object of the invention is the production 30 of means whereby the yarns that go to make up the finished product can be changed automatically during the knitting operation to give certain colors.

A sixth object of the invention is to automatically change the style of stitches in the product produced during the operation of the machine. A seventh object of the invention is the production of a knitting machine in which the usual cam chains are 40 not required.

In the accompanying drawings Fig. 1 represents a front elevation of an exemplification 45 of that portion of an adjustable automatic knitting machine which relates to this invention; Figs. 1^a, 1^b and 1^c indicate enlarged fragmentary portions of Fig. 1; Fig. 2 shows a top plan view of Fig. 1; Fig. 2^a represents an enlarged fragmentary portion of Fig. 2; Fig. 2^b shows an elevation of 50 Fig. 2^a; Figs. 2^c, 2^d and 2^e indicate enlarged fragmentary portions of Fig. 2; Figs. 2^f, 2^g and 2^h indicate enlarged fragmentary portions of Fig. 2 in different positions; Fig. 3 shows a partial right hand side view of

Fig. 2; Fig. 3^a indicates an enlarged view of 55 a fragmentary portion of Fig. 3; Fig. 4 represents an enlarged fragmentary portion of Fig. 1 and an enlarged section of Fig. 2^c on the line 4, 4; Fig. 5 indicates a top plan view of a portion of Fig. 4. Fig. 6 shows an enlarged fragmentary portion of Fig. 2; Fig. 7 indicates a partial section of Fig. 6 on the line 7, 7 with some coacting elements; Fig. 8 shows a top plan view of Fig. 8 on the line 9, 9; Fig. 10 shows a top plan view of some of the appurtenances of the needle guides; Fig. 11 is a section of Fig. 10 on the line 11, 11; Fig. 12 shows a plan view of a lug; Fig. 13 is a side view of Fig. 12; Fig. 14 shows a plan view of a lug; Fig. 15 is a side view of Fig. 14; Fig. 16 represents a plan view of a lug; Fig. 17 is a side view of Fig. 16; Fig. 18 shows a plan view 75 of a lug; Fig. 19 is a side view of Fig. 18; Fig. 20 shows an elevation of a lug; Fig. 21 is a section of Fig. 20 on the line 21, 21; Fig. 22 represents a front view of the stitch racking device; Fig. 23 is a left hand side view of Fig. 22; Fig. 24 shows a rear view of Fig. 22; Fig. 25 is a right hand side view of Fig. 22; Fig. 26 indicates a top plan view of Fig. 24; Fig. 27 represents an enlarged portion of some of the details 80 indicated in Fig. 1 showing particularly a dial actuating mechanism; Fig. 28 shows a top plan view of Fig. 27 and its coacting elements; Fig. 29 shows some of the elements of Fig. 28 in a changed position, Figs. 29^a, 90 29^b and 29^c show rear views of Fig. 27 with the elements in changed positions and a few elements added; Fig. 30 shows an elevation of the racking cylinder of the machine with one cover removed; Fig. 31 represents a section of Fig. 30 on the line 31, 31; Fig. 32 indicates a section of Fig. 31 on the line 32, 32; Fig. 33 indicates a top plan view of Fig. 30 with some of its coacting elements; Fig. 34 shows a plan view of an element of 100 the racking cylinder; Fig. 35 is a top plan view of Fig. 34; Fig. 36 shows a plan view of another detail of the racking cylinder. Fig. 37 shows an elevation of a controlling lever for the racking cylinder; Fig. 38 is a top plan view of Fig. 37; Figs. 38^a, 39 and 40, respectively, indicate sections of Fig. 37 on the lines a, a—i b—and c, c; Fig. 41

shows an elevation of elements that coact with the controlling lever of the racking cylinder; Fig. 42 represents an elevation of a cam drum; Fig. 43 shows a side view of Fig. 42; Fig. 44 indicates a front view of an adjusting dial; Fig. 45 shows an enlarged partial section of Fig. 3 on the line 45, 45; Fig. 46 represents an enlarged partial section of Fig. 3 on the line 46, 46 and Fig. 47 shows an enlarged partial section of Fig. 3 on the line 47, 47.

The machine (see Figs. 1, 2, and 3) in this instance is indicated with the table A, which is supported on one end on the double leg 13 indicated in its entirety by the letter B. The leg comprises the two vertical L shaped members with the front flanges 40, which are connected by the cross members 41 and 43. Bosses 44 are formed with the leg B. 20 Studs 46 are supported in the bosses 44. A front cross brace 47 is supported on the outer ends of the studs 46, and has formed therewith the central journal hub 48. A dial shaft 50 is journaled in the hub 48 at 25 its front portion and in one of the flanges 40 at its rear end. An adjusting dial is indicated in its entirety by the letter C.

The dial C (see Figs. 1, 2, 3, 6, 7, 28, 44 to 47) is indicated with the front wall 51 and the rim 52. A circular dove tail groove 53 is formed in the front wall 51 and the circumferential dove tail groove 54 is formed in the rim 52. An opening 55 extends through the wall 51 and joins with the 30 groove 53 and an opening 56 extends through the rim 52 and joins with the groove 54. A groove collar 58 is supported on the dial shaft 50 and bears on said dial C. A nut 59 in threaded engagement with the outer 35 end of the shaft 50 secures said collar 58 and dial C in place. A spur gear 60 is fastened to the dial shaft 50.

A journal bearing 65 (see Figs. 1, 2, 3, 45, 46 and 47) extends from the lower face 45 of the table A and has journaled therein the main driving shaft 66. A driving pulley 67 is fastened to one end of the shaft 66. A bevel pinion 68 is fastened to the other end of the shaft 66. A pair of journal bearings 69 and 70 extend from the lower face of the table A and have journaled therein the cross shaft 75. A bevel gear 76 is fastened to the cross shaft 75 and meshes with the bevel pinion 68. On the outer end of the shaft 75 is fastened thereto the locking lug 77. An auxiliary operating arm 80 has at its outer end the handle 81, and at its other end the sleeve 82 which is supported on the shaft 75. A triangular slit 83 is formed with the sleeve 82 which coacts with locking lug 77, to manually turn the cross-shaft 75. A spur gear 84 is fastened to the cross shaft 75. A pair of journal bearings 85 extend from the bottom face of the table A and have journaled therein the second cross shaft

86. A spur gear 87 is fastened to one end of the second cross shaft 86 and meshes with the spur gear 84. A spur gear 88 is fastened to the other end of the cross shaft 86. A second spur gear 89 is fastened to the shaft 70 86 adjacent to the spur gear 88. An elongated bracket 93 is fastened to the leg B, and has formed in its opposite ends the journal hubs 94 and 95. A journal stud 96 is fastened to the hub 94, and has journaled thereon the spur pinion 97 that meshes with the spur gear 88. A sprocket chain wheel 98 is also journaled on the journal stud 96 and is fastened to the spur pinion 97. A second journal stud 102 is fastened 80 to the hub 95 and has journaled thereon the second sprocket chain wheel 103. A sprocket chain 104 engages the sprocket chain wheels 98 and 103. A journal lug 105 extends from the sprocket chain 104 and 85 has journaled therein one end of connecting link 106 to be hereinafter described.

On the second cross shaft 86 (see Figs. 1, 3, 42, 43, 45 and 47) is fastened a cam wheel designated in its entirety by the letter 90 D, and comprises the hub 110, that has extending therefrom the flange 111. A pair of guide openings 112 and 113 are formed in the central flange 111, diametrically opposite each other. A guide wing 114 is fastened to the flange 111 which coacts with the guide opening 112 and a guide wing 115 is fastened to the flange 111 and coacts with the other guide opening 113.

A third cross shaft 120 (see Figs. 1, 2, 3 100 and 45) is journaled in journal bearings 121 extending from the upper face of the table A. A spur pinion 122 is loosely supported on the shaft 120 and meshes with the spur gear 89. A locking cam 123 is 105 fastened to the shaft 120. A pawl with the arms 124 and 125 is pivoted to the outer face of the pinion 122. The arm 124 coacts with the cam 123 and a spring 126 bears between the arm 125 and a lug 127 extending from the outer face of the pinion 122.

A boss 133 (see Figs. 2, 3, 37 and 38) with a pivot 134 extends up from the table A. A bell crank E with the arms 135 and 136 is pivoted to the pivot 134. A link 137 has 115 one end thereof pinned to the arm 136. A bell crank is indicated with the arm 138 and the sector arm 139 with the teeth 140. The arm 138 is pinned to the link 137. A link 141 is pinned to the arm 138, by means of 120 the pin 142. A cam rod is designated in its entirety by the letter F. The cam rod F comprises the member 145 with ears 146 at one end, and the ears 147 at the other end, which latter are at right angles to the ears 146. A cam member 148 has one end pivoted to the ears 147, by means of the pin 150. The said member 148 has formed on its upper edge the cam surface 151 and on its lower edge the cam surfaces 152 and 154. 125 130

During the operation of the machine the shaft 86 (see Figs. 1, 3, 41, 45 and 47) rotates in the direction of the arrow 155, whereby the spur gear 89 is turned in the same direction. By this means the rollers 90 and 91 revolve in the direction of the arrow 155, and at the same time can turn on their pivots.

The roller 90, during its revolution, contacts with the cam surface 152 of the member 148 and which latter is thereby swung up.

During the operation of the machine the cam rod F receives intermittent horizontal translation. When (see Figs. 37 to 41) the member 148 is located, so that the rollers 90 and 91 are in the plane of the line *a*, *a* the roller 91 raises said member 148. With the swinging up of the member 148, it bears on the arm 125 and thereby the arm 124 is unlocked from the cam 123, and the shaft 120 remains at rest and the roller 90 does not contact with the member 148. When the member 148 is located so that the rollers 90 and 91 coact therewith in the plane of the line *b*, *b*, then the member 148 is in its neutral position and is not swung up by contacting with either of said rollers, and the arm 124 remains locked with the cam 123 and rotates the shaft 120. When the member 148 is located so that the rollers 90 and 91 coact therewith in the plane of the line *c*, *c*, then the roller 90 will swing up the said member 148, and the arm 124 is unlocked from the cam 123 and the shaft 120 remains stationary. It is to be noted that the spur gear 89 on the shaft 86 is double the diameter of the pinion 122 on the shaft 120, so that when the gear 89 makes one revolution, the pinion 122 makes two revolutions. Therefore when the rollers 90 and 91 revolve with respect to the member 148 in the plane of the line *a*, *a*, then the shaft 120 remains at rest as a result of the contacting of the roller 91 with the member 148 for a half of a revolution of the shaft 86.

When the member 148 (see Figs. 38 to 41) is positioned so that the rollers 90 and 91 revolve in the plane of the line *c*, *c*, then through the roller 90, and during the other half of the revolution of the shaft 86, the shaft 120 also remains at rest. In other words, it is to be noted that the pinion 122 makes two revolutions for each revolution of the gear 89.

The roller 91 (see Figs. 1, 3, 38 to 41, 45 and 46) during one half of the revolution of the spur gear 89 and when contacting with the member 148 in the plane of the line *a*, *a*, swings up said member 148 and unlocks the pawl arm 124 from the cam 123, resulting in the stoppage of the shaft 120 for the first half of a revolution of the spur gear 89.

During the second half of the revolution

of the spur gear 89, when the roller 90 approaches the member 148, the latter roller does not actuate said member 148, and the shaft 120 thereby makes a revolution. When the member 148 is located to coact with the rollers in the plane *c*, *c*, the roller 90 instead of the roller 91 swings up the member 148, and the pawl arm 124 is unlocked from the cam 123 for the second revolution of the pinion 122 or for the second half revolution of the spur gear 89.

When the member 148 is located so that the rollers 90 and 91 actuate therewith in the plane of the line *d*, *d*, then both of said rollers contact with the member 148 and the pawl arm 124 is unlocked from the cam 123, and the shaft 120 remains at rest.

A lever 160 (see Figs. 1, 3, 28, 29, 45 and 47) is pivoted to the leg B by means of stud pin 161, and has pivoted at one end thereof the roller 162, which latter coacts with the cam wheel D. At the other end of the lever 160 is formed a disc 163 with a central opening 164 and the lug 165.

A ratchet lever 168 is indicated with the hub end 169, the nose end 168^a, the cam surface 172, a concaved portion 172^a and the driving tooth 170. A spring 172^b bears between the lever 168 and the lug 165. A journal stud 175 is supported on the member 41 and on which former are journaled the spur gears 176 and 177 that are fastened to each other. The gear 177 coacts with the tooth 170.

From the leg B extends a stud 180. A pawl 182 with the tooth 183 is pivoted to stud 180 by means of the screw pivot 181. The tooth 183 also coacts with the wheel 177. A spring 184 bears between a lug 184^a on the leg B and the pawl 182.

The cam wheel D (see Figs. 1, 12, 13, 28, 42, 43, 45 and 47) turns in the direction of the arrow 155 and the wings 114 and 115 cause the roller 162 to roll from one side of the flange 111 to the other alternately. By this means the lower end of the lever 160 is swung, and thereby the tooth 170 turns the wheel 177 in the direction of the arrow 185. The gear 176 meshes with the gear 60, and thereby the latter gear is intermittently moved with the movements of the gear 176 in the direction of the arrow 185. By this means the dial shaft 50 receives an intermittent rotation and carries with it the adjusting dial C. A lug indicated in its entirety by the letter G is detachably fastened to the adjusting dial C.

Upon the table A is supported a U shaped lever box indicated in its entirety by the letter H (see Figs. 1, 6, 7 and 22 to 26). The box comprises the front wall 190, side walls 191, 192 and the top flange 193. A cross piece 194 connects the walls 191 and 192. Levers 195, 196, 197 and 198 are located in the said box. The levers 195 and

196 are pivoted on the pin 199 supported in the walls 191 and 192, and the levers 197 and 198 are pivoted on a similar pin 200. The lever 195 has journaled to its lower end the roller 201 and at its upper end is formed the tooth 202. The lever 196 has journaled to its lower end the roller 203 and has formed at its upper end the tooth 204. The lever 197 has journaled to its lower end the roller 205 and at its upper end is formed the tooth 206. The lever 198 has journaled to its lower end the roller 207 and has formed at its upper end the tooth 208.

18 The wall 190 is extended at 214 and springs 215 bear between the extension 214 and the levers 195 and 196. Springs 216 bear between the cross-piece 194 and the levers 197 and 198. Bearings 217 and 218 extend from the wall 192.

19 A locking lever 220 is pivoted to the wall 192, by means of the pin 221. A tooth end 222 is formed with one end of the lever 220, which can lock with the teeth 140 of the 25 sector arm 139. A latch 225 at its lower end carries the lug 226 and at its upper end is formed an opening 227, that engages the end 228 of the lever 220. A slot 229 in the latch 225 engages a pin 230 extending from 30 the rear face of the wall 192. A lug 233 extends from the wall 192 and a spring 234 bears between the lug 233 and the lever 220. A rock shaft 235 is journaled in the bearings 217 and 218 and one end thereof 35 is fastened to the link 141. A trip arm 236 has one end fastened to the shaft 235 and at the other end of the trip arm 236 is formed the hook 237.

40 When the adjusting dial C moves, the lug G contacts with the lug 226 and thereby the latch 225 is moved upwardly. This causes the end 228 of the lever 220 to swing up, which lowers the knife edge 222 out of contact with the teeth 140 of the sector arm 139, to release the latter. The lug G next 45 contacts with the hook 237 of the trip arm 236, which swings the link 138 and the sector arm 139, whereby the cam rod F is moved in the direction of the arrow 240 (see 50 Figs. 2 and 3) and translates said rod as already described. To return the cam rod to its original position a second lug G' (see Figs. 1 and 13), placed at a predetermined distance back of the lug G on 55 the dial C contacts with a projection 226^a of the lug 226 (see Figs. 24 and 25), which causes the tooth end 222 of the lever 220 to unlock from the teeth 140 of the sector arm 139, and the tension of the spring 241 on 60 the shaft 235 returns the arm 139 to its initial position. It will be noted that one end of the spring 241 is fastened to the shaft 235 and its other end bears against the face of the wall 192.

65 In the table A (see Figs. 2, 6 and 7) is

formed a guide recess 246 and in which are guided the levers 250, 251, 252 and the unlocking lever 253. The lever 250 has formed at one end thereof the heel 254, and at its other end is formed a tooth notch 255. The lever 251 has formed therewith at one end the heel 256 and at its other end is formed the tooth notch 257. The lever 252 has formed at one end the heel 258 and at its other end is formed the tooth notch 259. Each of the levers 250, 251 and 252 have formed in their lower edge a pair of locking notches 260 and 261 and the unlocking lever 253 has formed in its bottom edge the locking notch 260.

70 A pair of cavities 265 are formed with the table A. A spring 266 is supported in each of said cavities. A slot 267 connects the cavities 265 and a locking bar 268 is guided in the slot 267 and extends into the cavities 265. The bar 268 bears on the springs 266 and locks with notches 260 of the levers 250, 251, 252 and 253.

75 A lever 272 at one end is pinned to the table A by means of the pin 273, and at about its central portion has pinned thereto the lever 250, by means of the pin 274. To the other end of the lever 272 is pinned the strike bar 275, by means of the pin 276. The end of the strike bar 275 has the round nose 277. A second lever 278 at one end is pinned to the table A, by means of the pin 279. At about the central portion of the lever 278 is pinned the lever 252 by means of the pin 280. At the other end of the lever 278 is pinned the second strike bar 281, by means of the pin 282. At the end of the rod 281 is formed the nose 283. A lug 284 extends from one side of the strike bar 281. A third lever 285 has one end thereof pinned to the table A, by means of the pin 286. The lever 251 is pinned to the lever 285 by means of the pin 287. At the other end of the lever 285 is pinned the third strike bar 289, by means of the pin 290. At the other end of the strike bar 289 is formed the nose 291.

100 The nose 291 of the strike bar 289 contacts with the nose 283 of the strike bar 281.

105 A sliding bolt 296 (see Fig. 2) is supported in the flanges 297 and 298 of the table A and has formed at one end thereof the foot 299. A roller 300 is pivoted to the said foot 299. At about the central portion of the bolt 296 is pivoted a lever 301, by means of the pivot 302. The lever 301 is pivoted to the table A by means of the pivot 303. A spring 304 bears between the swinging end of the lever 301 and the flange 305 of the table A.

110 A second sliding bolt 310 (see Fig. 2) similar to 296 is supported in the flanges 311 and 312 of the table A and has formed at one end thereof the foot 313.

115 A roller 314 is pivoted to the said foot

313. At about the central portion of the bolt 310 is pivoted a lever 315, by means of the pivot 316. The lever 315 is pivoted to the table A by means of the pivot 317. A lug 318 extends from the lever 315 and contacts with the lever 277, already described. A spring 319 bears between the swinging end of the lever 315 and flange 311 of the table A.

10 On the shaft 120 is fastened the guide drum designated in its entirety by the letter I (see Figs. 1, 2, 30 to 36). It comprises the barrel 326 with the annular flanges 327, the central inner rib 328 with the openings 329 and 330. An outer circumferential rib 331 extends from the barrel 326 and has formed therein an opening 332. At the opening 332, the rib 331 terminates in the tapered ends 333 and 334. 15 Openings 335 and 336 at right angles to each other, are formed in the barrel 326 and each extends from the vertical central plane of the said barrel to its sides. Similar covers 337 and 338 are fastened to the 20 sides of the barrel 326. Grooves 339 are formed in the covers 337 and 338.

The shaft 120 (see Figs. 2, 30 to 36) has the reduced portion 340 within the drum I. Cavities 341 and 342 are formed in said 25 reduced portions. A guide wing 345 is slidably guided in the opening 335, and extends from the table 346 located in the chamber K of the drum I. A vertical plate 347 extends below the table 346 and a stop shelf 348 extends from the plate 347. A second shelf 349 extends from the plate 347.

A guide plate 352 (see Figs. 2, 30 to 36) is slidably guided in the opening 336 and extends from the table 353, which latter is located in the chamber L of the drum I. A vertical plate 354 similar to 347 extends below the table 353 and a stop shelf 355 similar to 348 extends from the plate 354. A second shelf 356 similar to 349 extends from the plate 354. A spring 358 bears between the stop shelf 348 and the crown of the cavity 342, and a spring 359 bears between the stop-shelf 355 and the crown of the cavity 341.

50 A pair of similar connected cams 360 and 361 are provided for the guide drum I. Each of said cams has extending therefrom the forked end 362, that lock with each other. Each of the said cams has extending from its outer end the spindle 363 and to the latter are fastened the tappet bars 364 and 365. The forked ends when coupled to each other are located in the opening 330. The cam 360 coacts with the shelf 356 in the chamber L and cam 361 coacts with the shelf 349 in the chamber K.

To the top face of table A (see Figs. 2, 2^a and 2^b) is fastened a guide bar 370 by means of the screw pins 371. A slide 372 is 55 supported on the bar 370 and has formed

on one side thereof the raised guide block 373, and on the other side is formed the bifurcated lug 374. Rollers 375, 376 and 377 are journaled to the side of the guide block 373. A pair of lugs 378 are formed with 70 the block 373 and have hinged thereto, by means of the hinge pin 379, the latch plate 380. A spring 381 encircles the pin 379 and one end thereof bears on the slide 372 and the other end bears on the latch plate 380. 75

A connecting rod 385 has one end thereof pivoted to the lug 374 by means of the pivot 386 (see Figs. 2 and 3). A link 387 is pinned to the connecting rod 385, by means of the pin 388 and has formed at its 80 upper end the boss 389. An oscillating rod 390 has one end thereof fastened to the boss 389. A cam 391 is fastened to the rear end of the rod 390.

Upon the studs 46 is located and fastened 85 a plate 398 (see Figs. 1 and 3). A supporting bracket 399 extends up and is fastened to the plate 398.

A dial control plate is designated in its entirety by the letter M. The plate M is 90 indicated with the top edge 400, bottom edge 401, side edges 402 and 403, the front face 404 and rear face 405. Circular openings 406 and 407 are formed in the plate M. A notch opening 408 extends from the top edge 95 400 of the plate M. A rectangular opening 409 and a pair of annular openings 410 and 411 are formed in said plate M. A bolt 411^a with a wing nut 411^b connects the plate M to the bracket 399. A movable sleeve 412 100 engages the opening 406 and has formed therewith at one end the flange 413, with the curved opening 413^a. Said sleeve 412 has connected thereto the flange disc 414 with the curved opening 414^a. 105

A cover 415 is shown with a projection 416 extending from its inner face. The hub 169 of the ratchet lever 168 bears against the disc 163 of the lever 160.

The disc 163 (see Figs. 1, 28 and 29) of 110 the lever 160 bears against the flange disc 414. A bolt 418 maintains the hub end 169, the cover 415 with their interposed elements in proper lateral position. The bolt 418, by the oscillation of the lower end of the lever 160, moves in the curved opening 413^a in the flange 413 of the sleeve 412, and thereby the roller 162 at the upper end of the lever 160 is always maintained in close proximity to the flange 111 of the cam wheel D and is 115 prevented from travelling off the edge of the cam wheel D. (See Figs. 29^a, 29^b, 29^c, 45 and 47.) A latch 422 has extending from its front face the lugs 423 with the cam face 423^a between them and from its 120 rear face extends the contact lug 424. The latter is guided in the notch opening 408. An oscillating lever 425 is pivoted in front of the plate M, by means of the pivot 426 and at its upper end is pivoted to the latch 125 130

422, by means of the pivot 427. A locking lever is indicated with the members 428 and 429 and is located adjacent to the rear face 405 of the plate M, and is also pivoted on the pivot 426.

A bracket 433 (see Figs. 1, 3, 27 to 29) is shown with the rear flange 434 and the front flange 435. The said flange 434 is fastened to the plate M. A contact plunger N is indicated with the round ends 436 and 437, and the intervening square portion 438. The latter has a longitudinal opening 439. The end 436 is guided in the opening 407 of the plate M, and the end 437 is guided 15 in an opening in the flange 435.

A second contact plunger P is indicated with the rectangular portion 443 at one end and the cylindrical stem 444 at the other end. A depression 445 is formed in the portion 443. The portion 443 is guided in the opening 409 in the plate M, and the stem 444 is guided in an opening in the flange 435. A spring 446 encircles the stem 444 and bears between the rectangular portion 25 443 and the flange 435.

A pair of screws 448 and 449 extend respectively through the openings 410 and 411 and connect the lever 425 and the locking lever having the members 428 and 429. A 30 pair of ears 450 extend from the front face 404 of the plate M and have pivoted thereto the lever 451. The latter lever has formed therewith at one end the heel 452 and at the other end it is pivoted in the opening 439 of the square portion 438 of its coating plunger, by means of the pivot 454. Lugs 455 and 456 extend from the opposite sides of the lever 451. A spring 457 extends between the heel 452 and the front face 404 40 of the plate M. The lever 451 is pivoted to the ears 450, by means of the pin 458 and the lugs 423 straddle the lever 451.

A bracket 464 (see Figs. 1, 3 and 28) bifurcated at its upper end 465 is supported 45 upon and fastened to the plate 398. A lever 466 is pivoted at one end to the bracket 464. A spring 467 bears between the swinging end of the lever 466 and the plate 398. A cam lever 468 has one end pivoted to the lever 466, by means of the pivot 469. A cam surface 470 is formed in the inner lower edge of the lever 468. A pivot 471 is indicated at the top end of the lever 468. A 50 pair of brackets are indicated with the similar parallel upper members 472, 472^a and the diverging lower members 473, 473^a. The latter members are fastened to the front cross brace 47 and the members 472 and 472^a are fastened to the table A by means 55 not shown. An ear 474 extends from each of the members 472 and 472^a.

A latch lever 476 (see Figs. 3 and 28) is pivoted to the ears 474, by means of the pivot 477. A hook 478 is formed on one 60 end of the lever 476 and the other end of

the lever 476 is pivoted to the lever 468 by means of the pivot 471. A horizontal ear 483 extends from the member 472^a and has pivoted thereto the L shaped latch 484 by means of the pivot 485. A spring 486 encircles the pivot 485 and one end thereof 70 is fastened to the latch 484 by means of the pin 487 and its other end 488 bears against the ear 474. The office of the spring 486 is to maintain the L shaped latch 484 in its open position. A knee bracket 490 has one end fastened to the member 473^a and has pivoted thereto the roller lever 491, by means of the pivot 492. A roller 493 is 75 journaled to one end of the lever 491 and at the other end of the said lever is formed the bifurcated end 494. The roller 493 coacts with the cam surface 470, of the cam lever 468. The bifurcated end 494 engages a pin 495 extending from the contact plunger N. The roller 493 contacts with the lever 468 by reason of the tension of the spring 457 and its coacting elements. 80

A lug O (see Figs. 1, 16, 17 and 28) is 85 adjustably clamped to the adjusting dial C 90 in a predetermined location in the path of latch 484. With the movement of the dial C the lug O contacts with the latch 484 and swings it to its closed position, against the tension of the spring 486. By this means the hook 478 of the latch lever 476 locks the latch 484 in its closed position 95 under the tension of the spring 467, and the lever 468 rises.

By this means the roller 493 is located 100 in the cam surface 470. Thereby the plungers N and P are engaged with the cam 172 of the ratchet lever 168.

A pair of brackets 500 and 501 (see Figs. 1, 2 and 7) extend from the bottom face 105 of the table A and are fastened thereto. A pin 502 extends from the lower end of the bracket 500 and has supported thereon the lever 503. At one end of the lever 503 is formed a heel 504, and at its other end is a pin 505, by means of which it is connected to the lower end of the link 506. A second lever 507 is supported on the pin 502 and has formed at one end a heel 508 and at the other is a pin, not shown, by means of which it is connected to the link 510. A third lever is indicated with the parallel arms 511 and 512, connected by the connecting member 513.

A shaft 514 (see Figs. 1 and 2) is supported in the lower end of the bracket 501 and in turn supports the arms 511 and 512. A heel 515 is formed with one end of the arm 512, and the opposite end of the arm 511 is pinned to the link 516. A fourth lever 520 is fastened to the shaft 514, and at the other end of said fourth lever is formed a heel 522. An arm 525 has its hub end fastened to the front end of the shaft 514. A link 526 has its lower end pinned 110 115 120 125 130

to the outer end of the arm 525. A pair of brackets 528 and 529 extend up from and are fastened to the table A. A cover 530 is supported on and fastened to the bed plate A and covers the movable elements thereon. The said cover has formed therewith the pillow blocks 531 and 532. Brackets 533 and 534 are respectively supported upon the pillow block 531 and 532. 10 A pair of rollers 535 are journaled to the cover 530 and bears upon the guide block 375.

A shaft 540 (see Figs. 1 and 2) has one end supported in the bracket 529 and its 15 other end is supported in the bracket 533. A shaft 541 has one end supported in the bracket 528 and its other end is supported in the bracket 534. An arm 542 has its hub end fastened to the shaft 540 and its other 20 end is pinned to upper end of the link 506. A sleeve 542^a is loosely supported on the shaft 540 and has extending therefrom an arm 543. The arm 543 is pinned to the upper end of the link 510. A second arm 544 25 extends from the sleeve 542^a and has formed at its outer end the ratchet tooth 545. On the front end of the shaft 541 is fastened the arm 546.

The link 526 has its upper end pinned to 30 the outer end of the arm 546. A lever 550 has its hub end fastened to the shaft 541. The other end of the lever 550 is pinned to the link 551. The arm 555 has one end loosely supported on the shaft 541. The upper end of the link 516 is pinned to the 35 arm 555. The lever 556 is loosely supported on the shaft 541. To one end of the lever 556 is pinned the lower end of the link 557. A connecting bar 558 connects the arm 555 and the lever 556.

A ratchet arm 563 with the ratchet hook 564 has one end fastened to the shaft 540.

At the rear end of the table A is formed a raised portion 566 (see Figs. 1, 2, 3 and 45 5) and to which are fastened a pair of stanchions 567, each with the threaded bolt 568 at its lower end and the stud 569 at its upper end. A nut 570 locks each bolt 568 to said raised portion 566. The front frame member Q is supported upon the stanchions 567 and is in threaded engagement with the studs 569. A similar rear frame member, not shown, is provided for the knitting machine and is supported by 50 stanchions, not shown, similar to 567 and the latter are in turn supported on a leg, not shown, similar to B.

An inclined needle plate R' (see Figs. 1, 2, 3 and 5) has one end supported on and fastened to the member Q, and its other end is supported on a similar rear frame member, not shown. A similar inclined needle plate R is slidably supported on the member Q. A bracket 571 extends from the lower 60 face of the needle plate R and has pivoted

thereto the rollers 571^a which coact with the cam 391.

A guide stop bracket 572 is fastened to the member Q to guide and maintain in proper position one end of the needle plate R. A 70 similar bracket, not shown, is provided for the rear frame member. A pair of guide locking bars 573 and 574 are fastened to the members Q and the said rear frame member. Brackets 575 and 576 are respectively fastened to one end of the bars 573 and 574. 75

Rear brackets similar to 575 and 576, not shown, are provided for the rear end of the machine. A bar 577 connects bracket 575 with its rear bracket, not shown, and a bar 80 578 connects the bracket 576 and its rear bracket, not shown. A contact wing 580 with the openings 581 and 582 has formed therewith the hub end 583, which latter is fastened to the bar 577. A similar contact wing 585 is fastened to the rear end of the bar 577. A contact wing 589 with the opening 590 has formed therewith the hub end 591, which latter is fastened to the bar 578. A wing 593 similar to 589 is fastened to the 85 rear end of the bar 578. An arm 595 extends from the rear wing 593. A link 596 connects the wing 585, by means of the pin 597 and the arm 595 by means of the pin 598. 90

A brace 604 (see Figs. 1 and 5) is fastened at its ends to the brackets 575 and 576. A shaft 605 is supported at one end in the brace 604 and at its other end is supported in an opening 606 in the front frame member Q. A contact wing 607 has its hub end fastened to the shaft 605. A ratchet segment 608 with the teeth 609 has one end thereof fastened to the shaft 605 by means of a nut 610, engaging a threaded end of the shaft 605. The said teeth 609 coact with the 105 ratchet hook 564.

The link 557 connects the lever 556 and the contact wing 607.

A ratchet segment 612 has its hub end fastened to the shaft 577, and has formed therewith the ratchet teeth 613. The latter coact with the ratchet hook 564. 110

A carriage for knitting appurtenances is designated in its entirety by the letter S (see Figs. 1, 2, 4, 5 and 8) and has connected thereto the similar pair of housings respectively designated in their entireties by the letters T, T'.

The housing T comprises the roof 620 with the side wall 621. The roof 620 is slidably engaged with the locking bar 573. A cover 622 is spaced from and above the roof 620. A slide bar 623 is located between the roof 620 and cover 622. A heel 624 extends from one end of the bar 623, and at the other end thereof is formed the hook 625. A contact bar 626 bears against the side wall 621 and has formed therewith at its front end the steps 627. Guide openings 628 are formed 120 in the bar 626, and said bar is maintained 125

- in sliding contact with the wall 621 by means of the bolts 629, that extend through the openings 628 and are fastened to the side wall 621. A cam 630 extends from the contact bar 626. The said cam 630 coacts with hook 625. The end of the bar 626 opposite the steps 627 is pinned to the link 631. A bar is indicated at 635 which is similar to 626 and has formed at its front end a step 636 similar to 627. The bar 635 slides on the wall 621^a of the housing T'. A link 637 is pinned to the other end of the bar 635. Bars 638 and 639 extend from the housings T and T' and are connected by the cross-member 640. A lever 641 is pivoted to the cross member 640, and the arms of said lever are pinned to the links 631 and 637. A cam 642 similar to 630, but reversed in position extends from the bar 635. A slide bar 643 is fastened to the rear frame member not shown and engages the hub 644 of the depending arm 645, that extends from the cross member 640, by means of which the carriage S is slidably guided.
- 25 An arm 648 extends from the cross member 640 and has hinged thereto the bar 649. An oscillating lever 650 is pivoted at its bottom end to the rear leg (not shown) of the machine.
- 30 The top end of the lever 650 is pinned to the bar 649 and the central portion of the lever 650 is pinned to the connecting link 106.
- 35 Spaced from the bottom of each of the housings T and T' is located a bottom plate 655 (see Figs. 1, 5, 8, 9, 10 and 11), that have each formed therewith openings 656 and 657. A guide plate 658 can raise and lower in the opening 656 and has connected thereto the spacer plate 659 and the cover 660 with the cam 661. The cover 660 bears on the plate 655 beyond the opening 656. A guide rod 662 extends from the cover 660 through the roof 620. A spring 663 encircles the rod 40 662 and bears between the cover 660 and the roof 620. A guide plate 665 can rise and fall through the openings 657. It has connected thereto a spacer 666 and the cover plate 668. The latter has extending therefrom the cam 669.
- 45 A guide rod 672 similar to 662 with a spring not shown extends from the cover plate 668.
- 50 Contact bars 673 have formed therein the similar elongated guide openings 674 and one of each is slidably connected to the plates 655. Each of the bars 673 has formed at its opposite ends the contact step 675. In each contact bar 673 are also formed inclined cam bearing surfaces 677 and 678.
- 55 A pair of slideable guide plates 682 and 682^a are slidably located to the lower face of the bottom plates 655. Guide openings 683 are formed in each of the plates 655. A slide 684 is located upon the plate 655 and a projection 684^a thereof extends into the guide opening 683. A stem 685 with the wing nut 685^a extends from the slide 684. The stem 685 extends through a slot 686 in the roof 620. A spring 687 has one end fastened to the stem 685 and its other end is fastened to the pin 688 extending from the plate 655.
- 60 Contact bars 693 are indicated with the elongated slots 694 and by means of screws 695 are slidably connected to the lower faces of the roof 620. Each of the bars 693 has extending therefrom the cam lug 696, which is located in the path of the stem 685. A cam notch 697 is formed in each of the bars 693. A second stem 699 similar to 685 extends from the slide 700, similar to 684. A spring 701 similar to 687 has its ends fastened to the stem 699 and the plate 655. A lever with the arms 702 and 703 is pivoted on a pin 704 extending from the roof 620. The arm 702 is in the path of the cam notch 697 and the arm 703 is in the path of the stem 699. A slide 707 with the lugs 708 and 709 is supported on the locking bar 573 and has fastened thereto a yarn carrying arm 711, by means of a screw 712. A branch arm 713 with the upper eyelet 714 and the lower eyelet 715 extends from the arm 711. A slide 720 with the contact lugs 721 and 722 similar to 707 is supported on the locking bar 574. The slide 720 has fastened thereto the yarn carrying arm 725. The latter has formed therewith the eyelet 726. A branch arm 727 extends from the arm 725 and has formed therewith the eyelet 728.
- 65 The needle plates R and R' have each formed therewith the pointed ends 732, and the plurality of slots 733. Needles 734 each with the hook end 735 and the contact arm 736 are slidably located in the slots 733.
- 70 Spools not shown are provided for yarns that are threaded through the eyelets of the yarn carriers 711 and 725. The yarns are fed to the needles 734.
- 75 Appurtenances similar to those contained in and coacting with the housings T and T' are shown in the following United States patents, to wit: 232,834—244,079—244,353—246,843 and 304,178.
- 80 To use the machine the operator first determines the length of the material to be knitted, the style of stitches and the color of the different yarns to be used, the whole of which constitutes the pattern of the knitted material to be produced. The width of the material produced depends upon the number of needles employed in the machine.
- 85 All the adjustments of the machine are controlled by the dial plate C, and its detachably connected lugs. The operator first clamps the lug O to said dial in proper position for the required length of the material.

- 130

to be produced, and a plurality of other lugs for the style of the stitches and color of the yarn to be used.

The number of needles per inch in the 5 needle plates R and R' vary in different machines and indicate to the operator the size of the yarn to be used, and which can be varied somewhat, depending upon the nature of the knitted material to be produced. 10 This will also indicate to the operator the number of loops or stitches per inch of length of the material that can be produced.

Let it be supposed that the length of the knitted material is to be thirty inches, and 15 that ten double stitches will make up one inch of length. The lug O is clamped to the circumferential face of the dial C as indicated in Figs. 7 and 17, with its axial center line over the numeral 300 on the scale c' said member being in line with member 100 on the scale c'. The dial C must make one revolution for the length of the garment irrespective of its length. For each double 20 stroke or round of the carriage S the dial C is moved through one of its graduated divisions, in this instance of the scale c.

This is accomplished from the rotation of the main driving shaft 66. The shaft 66 rotates the cross shaft 75 through the bevel gears 68 and 76. The shaft 86 receives rotation from the shaft 75, through the gears 84 and 87. Thereby the gear 88 is turned, which latter turns the pinion 97, consequently the journal stud 96 is turned. By this means the sprocket chain wheel 98 is turned and moves the sprocket chain 104.

The latter through the connecting link 106 oscillates the lever 650. Thereby the 40 bar 649 is reciprocated and the carriage S through the arm 648 is also reciprocated.

The cam wheel D rotates with the second cross shaft 86 and moves the roller 162 of the lever 160 to the opposite sides of the 45 flange 111. Thereby the tooth 170 of the ratchet lever 168 turns the spur gear 177, and with it the gear 176. The gear 176 turns the gear 60 and with it the dial shaft 50 and the dial C. For each double stroke 50 of the carriage S, the dial C is moved through an angle of one of its divisions. One double stroke of the carriage S makes two stitches of length of the knitted material.

55 The dial C (see Figs. 1, 6, 7, 28 and 44), as indicated, has a scale a for its full circumference divided into 150 divisions, and a supplemental scale a' running in the reverse direction for one-third of its circumference indicating 50 divisions of the scale a with numerals from 150 to 200. A scale b also reversed to the scale a extends for one-third of the circumference of the scale a, starting at zero and extending to 100 60 opposite the fifty divisions of the scale a'.

The scales a, a' are used together for adjusting the machine for a length of material not exceeding 200 stitches. A scale c for its full circumference has two hundred divisions. A supplemental scale c' extends in 70 a direction opposite to the scale c for one-half of its circumference beginning over the numeral 200 of the said scale c and extending to 300. A scale d is also reversed to the scale c and runs for one-half of a circumference beginning in line with zero of scale c and ending with the division 200. 75

The lug O is as stated clamped opposite the division 300 on the scale c' representing one hundred divisions on the scale c, which latter for its full circumference has only two hundred divisions. Therefore one hundred divisions must be added to one revolution of the dial C for the required length of three hundred stitches or 30 inches of 80 length of the knitted material. This feature is accomplished with the assistance of the dial control plate M and its coacting elements, as follows. As already stated, when the lug O contacts with the latch 484 85 it swings it to its closed position. The hook 478 locks the latch 484 in its closed position, and the lever 468 with its cam surface 470 rises. Thereby the roller lever 491 is released from the control of the lever 468. 90 Before this time the plungers N and P were maintained out of contact with the ratchet lever 168 and the spur gear 177 was intermittently turned by the said ratchet lever 168. Now the said plungers N and P under 95 the control of the lever 451 and the springs 446 and 457 are released and their ends bear 100 against the ratchet lever 168.

The ratchet lever 168 (see Figs. 28 and 29) moves the spur gear 177 which will cause the concaved portion 172^a of the ratchet lever 168 to come opposite the plunger N, and the latter moves in the portion 172^a of the ratchet lever 168. At the same time the tooth 170 of the ratchet lever 168, 110 strikes the contact lug 424 of the latch 422, and moves the latter in the direction of the arrow 422^a and the cam face 423^a moves out of contact from the lug 456, and the plunger N can move as already stated into the concaved portion 172^a. The ratchet lever 168 is next moved in a direction opposite to the arrow 422^a and the plunger N lowers the ratchet lever 168, by the coaction of the cam 115 surface 172 to bring it out of contact with the spur gear 177. This also allows the plunger P to move over the cam surface 172. With the next swing of lever 160 the ratchet lever 168 moves in the direction of the arrow 422^a being under the plungers N and P and the spur gear 177 and the dial C 120 remains at rest. This operation allows the carriage S to make one double stroke for a round of stitches of the length of the material. The nose end 168^a of the lever 168 125

contacts with member 428 of the locking lever then the upper end of the lever 425 is swung in a direction opposite to the arrow 422^a, and through the pivot 427, will move 5 the latch 422 and the cam surface 423^a will contact with the lug 456 of the lever 451 and the plungers N and P will release the ratchet lever 168, so that with the next swing 10 of the lever 160 the said ratchet lever 168 will again move the spur gear 177 the distance of one tooth, and the dial C will again move through an angle of one division of the scales a or c. By the above method of 15 operation of the dial control plate M and its elements, the dial C will move through an angle of one of its divisions for one double stroke of the carriage S. It will be evident that in this instance, for the first half of the circumference of the scale, the carriage S 20 makes 100 double strokes and for the second half of the scale c the carriage S makes 200 double strokes.

The graduations of the scales a and c correspond to each increment of revolution of 25 the spur gear 177, when the operations of the ratchet lever 168 is not interrupted.

The supplemental scales a¹ and c¹ extend on the dial for a portion of its circumference and are indicated with two graduations 30 for one corresponding graduation on the scales a and c. By this means the number of stitches made are indicated when the rotation of the dial is intermittently interrupted by its coacting mechanism.

To further make the use of the scales on 35 the dial plate C clear, let it be required to make a knitted material 27 inches long.

This will require 270 double stitches or 270 double strokes of the carriage S for one revolution of the dial C. To obtain this result the lug O is clamped at the division 270 of the scale c'. This means that when the dial C moves from o on the scale c to the numeral 130 which is in line with 270, one 45 hundred and thirty double stitches will have been made by means of the movements of the ratchet lever 168 and its coacting elements. The lug O will now bring into action the mechanism of the plate M. There are 50 still remaining 70 divisions on the scale c for each of which by means of the plate M and its parts the carriage S makes two double strokes of the remaining 70 for each division on the dial C, or 140 double strokes 55 or stitches, making a total of 270 stitches, the number required.

After the desired length of the knitted material has been finished, it is necessary to again place the mechanism in the position 60 it was in before the lug O contacted with the latch 484. To accomplish this result, the lug U is clamped to the dial C over the division indicated at o. The said lug U contacts with the hook 478 of the latch lever 476, by 65 means of which the cam lever 468 is lowered,

which causes the roller 493 of the roller lever 491 to contact with one side of the lever 468. Thereby the lever 491, by means of its end 494 and the pin 495 withdraws the plungers P and N from the path of the 70 ratchet lever 168. The ratchet lever 168 is then in position to move the spur gear 177, and with it the dial C, through an angle equal to one of the graduations of said dial for each double stroke of the carriage S. 75

The scale d extends on the dial C for one-half of a circumference, and is divided into two hundred divisions for one hundred divisions of the scale c.

To produce different kinds of stitches in 80 the knitted material the strokes of the needles along their longitudinal axes are varied. This is accomplished by the movable guide plates 665 and 658 (see Figs. 5, 8 and 10) and the slideable guide plates 682 and 682^a, 85 by means of the cams 677 and 678 of the contact bar 673, and the cam lug 696 and cam notch 697 of the bar 693. The cam notch 697 coacts with the arm 702 of its lever.

The contact bars 673 and 693 move with 90 the carriage S and at the ends of the stroke of said carriage the said bars meet the contact wings 580 and 589 in the front end of the machine and the contact wings 585 and 593 of the back end of the machine. 95

Thereby the said bars 673 and 693 change their positions with respect to the carriage S. By this means through the cams 677, 678, cam lug 696, cam notch 697 and arms 702 and 703, the guide plates 658, 665, 682 100 and 682^a are moved, which changes the strokes of the needles 734 and the style of the stitches is varied. To accomplish this result the front contact wings 580, 589 and the rear contact wings 585 and 593 with 105 their openings have to be located in different positions for different strokes of the contact bars 573 and 593. The movement of the said contact wings to different positions is accomplished as follows. The contact wings are 110 connected as already described and move simultaneously.

The lug X (see Figs. 1 and 2) is clamped to the circumferential surface of the dial C in a predetermined position by the operator. For instance let it be supposed that the first fifty stitches of the garment are of a certain style, then the lug X is clamped to the dial C over the division o of the scale c. As the dial C moves the contact ends x' 115 and x^a of the lug X will raise the heel 508 of the lever 507 and the heel 522 of the lever 520. The lever 507 and the connections between it and the arm 544 will release the ratchet tooth 545 from the teeth 613 of the 120 ratchet segment 612. At the same time the lever 520 and its connections with the contact wing 580 will swing the latter in the direction of the arrow 580^a, and thereby the remaining contact wings 585, 589 and 593 125 130

are simultaneously swung up through the same angle. After the dial C has moved one tooth the heel 508 of the lever 507 is released from the contact end x' , and the ratchet tooth 545 by reason of the tension of the spring 502^a locks the ratchet tooth 545 with one of the teeth 613 of the ratchet segment 612, and thereby the contact wing 580 and the other wings are held in position. To produce different styles of stitches the contact wing 580 and said other wings are located at different angles and which is accomplished by varying the height only of the contact x^3 of the lug X.

With different positions of the contact wing 580 and the wings that move therewith, the contact bars 573 and 593 receive different strokes and consequently the needles 734 receive different strokes as already described.

To change the yarns in the knitted material to produce different colors therein, the contact wing 607 (see Figs. 1, 2 and 8) must be located in different positions. This is also accomplished by means of the lug X. The contact ends x^2 and x^4 with the movement of the dial C will raise the heels 504 and 515 of the levers 503 and 512. The lever 503 and the connections between it and the ratchet arm 563, will release the ratchet hook 564 from the ratchet teeth 609 of the segment 608. At the same time the contact end x^4 of the lug X raises the lever 512 and through its connections with the contact wing 607 the latter is moved to a position opposite one of the steps 627 of the contact bar 626. By this means and by virtue of the movements of the carriage S the positions of the bars 626 and 635 through the cams 630 and 642 are contacted with the hooks 625 of the bars 623. By this means the heels 624 contact with the lugs 708, 709, 721 and 722 of the slides 707 and 720. By this means the yarn carrying arm 711 or 725 is moved with the carriage S. After the dial C has moved one tooth further, the lever 503 is first released from the contact end x^2 of the lug X, and the ratchet tooth 564 of the lever 563, by reason of the tension of a spring similar to 502^a, locks with one of the teeth 609 of the segment 608, and thereby the contact wing 607 is held in its set position. To locate the contact wing 607 in different angular positions opposite any of the steps 627 and 636 of the bars 626 and 635, the contact end x^4 of the lug X is made of different heights. By means of a plurality of lugs X with different heights of contact ends, a plurality of different colored yarns and different stitches can be obtained for the knitted materials.

To produce rack or zigzag stitches in the knitted material by the machine the needle plate R with its needles 734 must be shifted relatively to the needle plate R', for each

double stroke of the carriage S. This is accomplished by the lug W that is clamped to the dial C. In the case indicated in the drawings (see Fig. 7) the lug W contacts with the roller 205 of the lever 197 having 70 the tooth 206, and thereby the lever 250 is moved, which swings the lever 272. The latter moves the strike bar 275, which is thereby placed with its nose 277 in the path of the guide block 373, that moves with the slide 372 on its guide bar 370. This causes the strike bar 275 to swing and bear against the hub 318 of the lever 315, against the tension of the spring 319. Thereby the sliding bolt 310 is moved toward the guide drum I, and the roller 314 is located in the path of the tappet bar 365. When the said drum rotates with this location of the roller 314, the guide wing 345 of the drum I is raised. With the rotation of the drum I the roller 377 is guided by the wing 345, to travel on the right hand side of the rib 331 as indicated in Fig. 2. By this means the slide 372 is moved to the right and through the connecting rod 385, the link 387 swings and turns the cam 391. By this means through the rollers 571^a the needle plate R is moved the distance between a pair of its needles. This movement occurs when the carriage S is at the end of its double stroke adjacent to the rear of the machine, then the needles 734 and 735 are in their lowest position and can clear each other. In this position of the lever 250 the locking bar 268 under the tension of the springs 266 locks with said lever 250 in its notch 261. With the next revolution of the guide drum I, the roller 376 takes the path described for the roller 377 and the needle plate R is again moved in the same direction for the distance between a pair of the needles 734 and 735. With the next revolution of the guide drum I, the roller 375 also takes the same path described for the rollers 376 and 377, and the needle plate R is again moved in the same direction for a distance equal to that between a pair of the said needles. When the roller 375 is located on the right hand of the rib 331, the end 380^a of the latch plate 380 comes in contact with the lever 301. This will move the sliding bolt 296 with its roller 300, in the path of tappet bar 364. With the rotation of the drum I the tappet bar 364 by its coaction with the roller 300, will cause the guide wing 345 to be lowered and the guide wing 352 to rise. With the next three revolutions of the drum I the rollers 375, 376 and 377 one after the other will return the needle plate R to its original position and thereby the directions of the stitches of the knitted material will form a three stitch zigzag. These three stitch zigzags continue to be formed until the mechanism thereof is released. This is accomplished by an- 130

other lug W on the dial C, which will contact with the roller 203 of the lever 196. The said lever 196 will move forward the lock lever 253, which has only formed 5 therein the one notch 260 and thereby the locking bar 268 is lowered and the lever 250 under the tension of the spring 215 will move to its original position.

In case a two stitch zigzag is required then 10 a similar lug W on the dial C is located to coat with the roller 207 and thereby the lever 198 will move the lever 252. The latter will swing the lever 278 which will bear on the lever 272, and thereby the strike bars 15 275 and 281 will be located in the path of the end of the slide 372 and the end 380^a of the latch plate 380. Thereby the rollers 377 and 376 will follow one after the other for each revolution of the drum I, and the needle 20 plate R will move twice and the roller 376 will be located on the right hand side of the rib 331, and the end 380^a of the latch plate 380 will then bear against the nose 283 of the strike bar 281. By this means the lug 25 284 will bear against the lever 301 and the roller 300 will perform its function, to return the needle plate R to its original position after two double strokes of the carriage S.

In case a one stitch zigzag is required, another similar lug W will coat with the roller 205 of the lever 197 and thereby the lever 251 is moved. The lever 251 swings the lever 285 and the lever 285 swings the 30 levers 278 and 272. Thereby the strike bars 275, 281 and 289 are moved and located in the path of the guide block 373, and the end 380^a of the latch plate 380. This causes the roller 314 to raise the guide wing 345, which guides the roller 377 to the right hand 35 side of the rib 331, by means of which the needle plate R through its connected elements will move forward the distance between two of the needles of the machine. 40 This again locates the end 380^a in contact with the nose 291 of the lever 289. This will move the lever 281 and the latter will contact with the lever 301 and the roller 300 will be moved into the path of the tappet bar 50 364, and the guide wing 352 will rise by means of which the roller 377 will cause the needle plate R to return to its original position.

In each of the style of zigzag stitches the 55 operation continues until the similar lug W bears against the roller 203 of the lever 196 (see Figs. 1, 7, 18, 19, 23 to 25), whereby the lock lever 253 lowers the locking bar 268, by means of which any or all of the levers 60 250, 251 and 252 are released, and under the tension of the springs are located in the original positions as already described.

As already indicated the shaft 120 with its guide drum I makes two revolutions to each 65 double stroke of the carriage S. The needle

plate R is longitudinally moved at the ends of the strokes of the carriage S. At these points the needles 734 and 735 are out of contact with the guide plates below the bottom plate 655. By reason of this disposition 70 of parts the needle plate R can be moved when the carriage S is located at either end of its stroke. As the movements of the

needle plate R are controlled by the rotations of guide drum I, the said needle plate R can 75 be moved for each single stroke of the carriage S. By this means the zigzag stitches can be varied. The various zigzag stitches can be produced by means of the cam rod F

with its cam member 148, having the cam 80 surfaces 151, 152, 153 and 154. When the member 148 is located in the plane of the line a, a one of the rollers of the spur gear 89 will raise the member 148, by means of which the arm 124 of its pawl is unlocked 85 from the cam 123, and thereby for one single stroke of the carriage S or for a half revolution of the machine the guide drum I, through the shaft 120 will remain at rest, and during the second single stroke of the carriage S, the guide drum I will turn, because the other roller of the spur gear 89 90 will not contact with the said member 148, which allows the drum I to coat with one of the rollers 375, 376 or 377, by means of which the plate R through the interposed elements will be moved. In this instance or when the rollers 90 and 91 are revolving in the plane a, a the needle plate R will move when the carriage S is located at the end of its double stroke adjacent to the rear end of the machine. By this means the zigzag 95 stitches of the knitted material, irrespective of the style of its zigzags will be visible on the top face of the material. When the rollers 90 and 91 coat with the member 148 in the plane of the line c, c the plate R will move when the carriage S is located at the end of its double stroke adjacent to the front 100 end of the machine, and the zigzags of the knitted material will be visible on the other or lower side thereof. When the rollers 90 and 91 coat with the member 148 in the plane of the line b, b both the rollers 90 and 91 do not contact with the member 148, and the guide drum I rotates without interruption, and the needle plate R will move at the end of every single stroke of the carriage S. By this means the zigzag of the 105 knitted material will be visible on both sides thereof. When the rollers 90 and 91 are located in the plane of the line d, d both of said rollers will contact with the member 148 and pawl arm 124 will be unlocked from the cam 123, and the guide drum I will remain 110 at rest, and thereby the plate R remains at rest. All the functions of the cam rod F are obtained by placing it in different positions by means of lugs G of different heights.

Referring again to the use of the dial 115

130

plate C (see Figs. 1 and 44), with its scales, as already indicated, the scale *a* for its full circumference is divided into 150 divisions, and the scale *a'* running in a reverse direction for one-third of a circumference with divisions of the scale *a*, from 150 to 200. So a length of material up to 200 stitches for a full revolution of the dial C can be made by locating the lug O opposite any of the 5 graduations on the scale *a'*. The machine will produce stitches corresponding to the number indicated on the scale *a* opposite the lug O plus double the number indicated on the scale *a'*. The scale *b* running in the 10 same direction with the scale *a'* indicates to the operator, the number of single stitches corresponding to the double stitches on the scale *a'*.

It will be noted that the scale *c* for its 20 full circumference is divided into 200 divisions and the scale *c'* running in a reverse direction for one half of a circumference of the scale *c* is indicated with members from 200 to 300; and the purpose of the 25 scale *c'* is similar to that of *a'*. The purpose of the scale *a'* which runs in the direction of the scale *c'* indicates to the operator the number of single stitches for the double stitches of the scale *c'*, obtained by 30 the action of the lug O.

If more stitches are required for a length of material than the highest graduation indicated on the present dial plate C, then other graduated scales would be indicated on 35 the dial plate C, and the gear 177 would be made with more teeth to coact with the new graduated scale.

It is to be understood that various modifications may be made in the invention without departing from the spirit thereof and the present exemplification is to be taken as 40 illustrative and not limitative thereof.

Having described our invention what we 45 desire to secure by Letters Patent and claim is:

1. In a knitting machine the combination of knitting appurtenances, an adjusting dial journaled in the machine, means to intermittently rotate the dial, scales indicated on the dial, means in the machine for turning said dial a complete revolution, means in the machine to operate the knitting appurtenances for one cycle of their operations for a movement of said dial through an angle 50 between a pair of adjacent divisions of one of its scales and means in the machine to operate said knitting appurtenances an increased number of times for a movement of the dial through an angle of a second scale 55 thereon, to obtain for one revolution of the adjusting dial the predetermined length of the material to be knitted, and its predetermined pattern of stitches.

2. In a knitting machine the combination 60 of a reciprocating carriage coacting with

knitting appurtenances, an adjusting dial in the machine, means to intermittently rotate the dial during the reciprocations of the carriage, a circular scale on the dial for a full circumference, a supplemental scale on the dial extending in a direction reversed to the direction of the first scale and for only a portion of a full circumference, appurtenances in the machine for rotating the dial a complete revolution, appurtenances to reciprocate the carriage a double stroke for one division of the arc of the first scale included between its full circumference minus a predetermined portion of the arc of the supplemental scale and means in the machine to reciprocate the carriage an increased number of times for each graduation of the supplemental scale and for a predetermined portion thereof, to obtain for one revolution of the adjusting dial the predetermined length of the material to be knitted.

3. In a knitting machine the combination of a reciprocating carriage coacting with knitting appurtenances, an adjusting dial in the machine, means to intermittently rotate the adjusting dial during the reciprocations of the carriage, a circular scale on the dial indicated thereon for a full circumference, a supplemental scale on the dial extending in a direction reversed to the direction of the first scale and for only a portion of a full circumference, appurtenances in the machine for rotating the dial a full revolution, appurtenances to reciprocate the carriage a double stroke for one division of the arc of the first scale included between its full circumference minus a predetermined portion of the arc of the supplemental scale, and means in the machine to reciprocate the carriage two double strokes for each graduation of the arc of the supplemental scale that with the said portion of the first scale makes a complete circle, to obtain for one revolution of the dial the predetermined length of material to be knitted.

4. In a knitting machine the combination of a reciprocating carriage coacting with knitting appurtenances, an adjusting dial in the machine, means to intermittently rotate the dial during the reciprocations of the carriage, a circular scale on the dial for a full circumference, a supplemental scale on the dial extending in a direction reversed to the first scale and for only a portion of the full circle, appurtenances in the machine for rotating the dial a complete revolution, appurtenances to reciprocate the carriage a double stroke for each division of a predetermined number of divisions of the first scale and to reciprocate the carriage two double strokes for a number of the divisions on the second scale, which divisions added to the used divisions on the first scale make a complete circumference.

- a third scale on the dial located in line with the supplemental scale with divisions and each corresponding to one double stroke of the carriage and double in number to said supplemental scale, and means to change the stitches for any portion of the third scale.
5. In a knitting machine the combination of a main driving shaft, a reciprocating carriage for knitting appurtenances, connections between the said shaft and said carriage, an adjusting dial for controlling the knitting operations journaled in the machine, a rotating shaft journaled in the machine, connections between the said shaft and the main driving shaft, a cam wheel fastened to said second shaft and having a central flange with a pair of guide openings therein, a guide wing for each of said openings, a lever pivoted in the machine, a roller journaled at one end of said lever coacting with the said cam wheel and its flange and guide openings, a ratchet lever with a driving tooth pivoted to the other end of the lever, a spur gear journaled in the machine coacting with said driving tooth to rotate the gear one tooth for each double stroke of said carriage, and means to rotate the said gear for each two double strokes of said carriage and connections between said gear and said dial.
6. In a knitting machine the combination of a main driving shaft, a reciprocating carriage for knitting appurtenances, a second shaft, connections between the shafts to transmit rotation from the driving shaft to the second shaft, a dial control plate in the machine, a lever fulcrumed in the machine, means to swing the upper end of the lever, a bolt at the lower end of the lever engaging an elongated opening in the dial control plate, a ratchet lever having a driving tooth, a cam surface, a concaved portion and a nose end supported on said bolt, a dial shaft journaled in the machine, a dial plate fastened to the dial shaft, a spur gear journaled in the machine, connections between the spur gear and the dial shaft, a pair of brackets supported in the machine, a latch lever pivoted to the said brackets, a latch pivoted below and in the path of said latch lever to be enabled to lock the latch lever, a lug on the dial to swing the latch to lock the latch lever with said latch, a cam lever with one end pinned to the latch lever, a third bracket supported in the machine, a lever with one end pinned to the latter bracket, a spring bearing up against the swinging end of the third lever, the cam lever with its lower end pinned to the third lever, a knee bracket extending from the pair of brackets, a roller lever with a bifurcated end pivoted to the knee bracket, a roller journaled to said roller lever, said roller in the path of the cam lever, a dial control plate in the machine, a

bracket extending from the dial control plate, a pair of contact plungers slidably supported on the latter bracket, a pin extending from one of said plungers engaged by the bifurcated end of the roller lever, a lever having a lug pivoted to the dial control plate and swinging said contact plungers to reciprocate the same through openings in the dial control plate, a spring encircling one of the plungers tending to move it through an opening in the dial control plate, a spring bearing between one end of the latter lever and the dial control plate, a latch having a cam face and a contact lug slidably supported on the dial control plate, said cam face in the path of the hub of the latter lever, an oscillating lever pivoted to the dial control plate with its upper end pivoted to said latch, a locking lever with a pair of members on the opposite side of said dial control plate and connections extending through openings in the dial control plate between the oscillating lever and the locking lever, one of the arms of the locking lever adapted to lock the nose end of the ratchet lever and with the swinging of the fulcrumed lever, said ratchet lever is reciprocated and swings the locking lever and through the lever connected to said locking lever and thereby the latch having the cam face engages the hub of the lever engaging the plungers, whereby the said plungers are moved out of contact with the concaved portion and cam surface of the ratchet lever, and the latter swings up and its driving tooth engages said spur gear, simultaneously the nose end of the ratchet contacts with the contact lug of the latch and thereby the plungers move above and in the path of the ratchet lever, and with the next movement of the ratchet lever the driving tooth thereof is out of contact with said spur gear.

7. In a knitting machine the combination of a main driving shaft, a reciprocating carriage for knitting appurtenances, connections between said shaft and said carriage, an adjusting dial for controlling the knitting operations of the machine, a lug fastened to the dial, connections between the main driving shaft and said dial to turn said dial intermittently during the reciprocations of the carriage, a pair of needle plates in the machine, reciprocating needles supported in the needle plates, guide plates to reciprocate the needles during the reciprocations of the carriage, contact bars slidably supported on the carriage, steps at the ends of some of the bars, controlling means between said contact bars and said guide plates, a lug clamped to the adjusting dial, a pair of levers each with a heel pivoted in the machine, the said heels in the path of said lug, two pairs of swinging contact wings having openings pivoted in the machine, connections

between the wings to swing them simultaneously, connections between one of the levers and said contact wings, a ratchet segment extending from one of said contact wings, 5 an arm with a ratchet tooth pivoted in the machine to lock the ratchet segment and hold the contact wings in different positions, connections between said arm and the second lever, said wings and their openings 10 in the path of the ends of the contact bars, to change their positions and thereby change the positions of the guide plates that control the strokes of the needles to change the style of the stitches produced in the knitted 15 material.

8. In a knitting machine the combination of a main driving shaft, a reciprocating carriage for knitting appurtenances in the machine, connections between said shaft and 20 said carriage, an adjusting dial for controlling the knitting operations of the machine, a lug fastened to the dial, connections between the main driving shaft and said dial to turn the dial intermittently during 25 said reciprocations of the carriage, a pair of bars having steps at one end slidably supported on the carriage, yarn carrying arms slidably supported in the machine, locking means on the carriage to lock the yarn carriers thereto, an oscillating lever to connect 30 the said bars, cams on the bars coacting with said locking means, a pair of levers each with a heel pivoted in the machine, the said heels in the path of said lug, a swinging contact wing pivoted in the machine, connections 35 between said wing and one of the levers, a ratchet segment moving with the contact wing, a ratchet arm with a ratchet tooth pivoted in the machine, connections 40 between the ratchet arm and the second lever, the side of said contact wing coacting with the different steps of the said bars to move them to different positions and lock a 45 yarn carrier to the said carriage and thereby feed different yarns to the needles of the machine, said ratchet segment and ratchet arm locking the contact wing in position.

9. In a knitting machine the combination 50 of a main driving shaft, a reciprocating carriage for knitting appurtenances in the machine, connections between said shaft and said carriage, an adjusting dial journaled in the machine, lugs on the dial to control said appurtenances, connections between the main driving shaft and said dial to turn it 55 intermittently during reciprocations of the carriage, a lever box fastened to a table of the machine, four levers pivoted in said box, a roller journaled at the lower end of each lever and each in the path of one of said lugs to swing its lever thereby, a tooth at the upper end of each lever, a set of three levers and a lock lever slidably supported 60 on said table, the latter four levers having tooth notches engaging said teeth at

one end and said three levers having each a pair of locking notches in the bottom face and said locking lever having one locking notch in its bottom face, a locking bar 65 flexibly supported on the table below said three levers and said locking lever and enabled to engage the said notches of the three levers and the one notch in said locking lever, a second set of three levers with one end of each pinned to the table, 70 the latter three levers pinned at about their central portions to the first set of three levers, a strike bar with one end pinned to each one of the second set of levers, a slide movable on the table of the machine, three rollers 75 journaled on the slide, a latch plate pinned to one end of the slide in the path of a pair of the strike bars, a guide drum journaled in the machine, connections between the drum and driving shaft, a circular rib with 80 a guide opening on the drum, movable guide wings carried by the drum coacting with said guide opening, a lever pivoted to the table of the machine with one end adjacent to one of said strike bars, a spring bearing 85 against said end of the lever, a sliding bolt movably supported on the table and pivoted to the other end of the latter lever, a roller journaled to one end of the said bolt, a second lever pivoted to the table of the machine with one end adjacent to the other two strike bars, a spring bearing against said end of the latter lever, a second sliding bolt movably supported on the table and pivoted to the other end of the latter lever, a roller 90 journaled to one end of said bolt, means on the said guide drum coacting with the rollers of the bolts to raise and lower the guide wings of the said guide drum, the rotations 95 of the drum through its wings engaging the rollers of the slide, one at a time causing said slide bar to reciprocate, the said plate on said slide adapted to strike at one of its ends, and the end of the latch plate adapted to strike the other two strike bars and also 100 the lever adjacent to the latter strike bar. 105

10. In a knitting machine the combination of a main driving shaft, a reciprocating carriage for knitting appurtenances in the machine, connections between said shaft and said carriage, an adjusting dial journaled in the machine, lugs on the dial to control the said knitting appurtenances, connections between the main driving shaft and said dial 115 to turn it intermittently during the reciprocations of the carriage, a rotating guide drum, connections between the drum and the dial to turn the drum, a slide reciprocated with the turning of the drum, a connecting rod with one end pivoted to the slide, a link with one end pivoted to the other end of the connecting rod, an oscillating rod supported in the machine and the other end of said link connected to one end of the oscillating rod, a needle plate slidably supported 120

125

130

in the machine, a pair of rollers journaled to the said needle plate, and a cam on the rod coacting with said rollers to move the needle plate.

5 11. In a knitting machine the combination of a table, a main driving shaft journaled below the table, a reciprocating carriage for knitting appurtenances in the machine, connections between said shaft and said carriage, an adjusting dial journaled in the machine, lugs on the dial to control the knitting appurtenances, connections between the driving shaft and said dial to turn it intermittently during the reciprocations of 15 the carriage, a shaft journaled over the table, a guide drum fastened to the latter shaft, a needle plate slidably supported in the machine, connections between the needle plate and the guide drum to move the said plate 20 and means to intermittently rotate the shaft of the guide drum.

12. In a knitting machine the combination of a table, a main driving shaft below the table, a reciprocating carriage for knitting appurtenances in the machine, connections between said shaft and said carriage, an adjusting dial journaled in the machine, lugs on the dial to control the knitting appurtenances, connections between the driving shaft 25 and said dial to turn it intermittently during the reciprocations of the carriage, a shaft journaled over the table, a guide drum fastened to the shaft, a needle plate slidably supported in the machine, connections between the needle plate and the guide drum to move said plate, a spur pinion loosely supported on the guide drum shaft, a locking cam fastened to the guide drum shaft, a pawl 30 with a pair of arms pivoted to the said spur pinion, one of said arms adapted to lock with said locking cam, a spring bearing against

the other arm of said pawl, a second shaft journaled in the machine, a spur gear on the latter shaft meshing with the spur pinion, a pair of rollers journaled to the latter spur gear, a lever box fastened to machine, a latch 45 slidably supported on the lever box, a lug with a projection extending from the latch, a rock shaft supported on the lever box, a spring for the rock shaft to swing it in one direction, a trip arm with a hook fastened to one end of the rock shaft, both the lug and its projection and the hook of the trip arm in the path of a lug on the dial, a link 50 with one end fastened to the other end of the rock shaft, a bell crank with its fulcrum pivoted to the other end of the link, teeth formed with one arm of the bell crank, a second bell crank pivoted to the table of the machine, a link connecting the said bell 55 cranks, a cam rod pinned to an arm of the second bell crank, a cam member fastened to the cam rod, said cam member having cam surfaces on its top and bottom edges, said cam rod located in different positions by virtue of the effect of different shaped lugs of the dial plate on the said trip arm, and thereby the different cam surfaces are caused to contact with the rollers of said spur gear and thereby actuating the pawl on the spur 60 pinion to lock and unlock the spur pinion from its shaft, to intermittently or continuously rotate or stop the rotations of the guide drum.

Signed at the borough of Manhattan, city 75 of New York in the county of New York and State of New York this 27th day of July A. D. 1922.
